US00D675160S

(12) **United States Design Patent**
Tanaka et al.

(10) **Patent No.:** US D675,160 S
(45) **Date of Patent:** ** Jan. 29, 2013

(54) **CONTROLLER FOR BATTERY**(75) Inventors: **Yosuke Tanaka**, Kobe (JP); **Katsuyuki Tomonaga**, Osaka (JP)(73) Assignee: **SANYO Electric Co., Ltd.**, Moriguchi-shi, Osaka (JP)(**) Term: **14 Years**(21) Appl. No.: **29/414,017**(22) Filed: **Feb. 23, 2012**(30) **Foreign Application Priority Data**

Sep. 16, 2011 (JP) 2011-021269
(51) **LOC (9) Cl.** 13-02
(52) **U.S. Cl.** D13/123; D13/110; D14/313
(58) **Field of Classification Search** D14/240,
D14/300, 308, 313, 348-356, 364-368; D13/107,
D13/110, 123, 124, 133, 162, 184, 199;
312/223.1-223.3, 351.11; 360/99.01-99.12;
369/34.01-36.01; 361/679.31-679.33, 679.37,
361/679.39, 679.46, 679.53, 679.4, 679.41,
361/727

(74) Attorney, Agent, or Firm — Westerman, Hattori,
Daniels & Adrian, LLP(57) **CLAIM**The ornamental design for a controller for battery, as shown
and described.**DESCRIPTION**FIG. 1 is a right front perspective view of a controller for
battery, showing our new design;

FIG. 2 is a left rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines illustrate environmental structure only and
form no part of the claimed design.**1 Claim, 8 Drawing Sheets**FIG. 1
